CAMLESS REGULATOR FOR GRADING DEVICES

Charles C. Thomas, Medford, Mass., assignor to
North American Research Corporation, Cambridge, Mass., a corporation of Massachusetts

Application June 19, 1948, Serial No. 34,031

5 Claims. (Cl. 33—147)

1

This invention relates to grading machines used in the shoe industry, particularly to a mechanism for regulating the action of the Nichols type grader, disclosed in Pat. No. 1,130,321, which is used for measuring the thickness of soles, heel lifts, counters, taps, and similar leather blanks.

A grading machine of the type to which this invention relates employs as the detecting element a pair of continuously driven rolls. The vertical position of the upper roll is fixed. The lower roll is movable up and down and is spring-pressed toward the upper roll. The motion of the lower roll is communicated through a yoke and a pair of connecting rods to a transmission lever which may operate various mechanisms for indicating, skiving, sorting, marking, and distributing the leather blanks in accordance with the measured thickness. The blanks may be fed to the rolls manually or automatically. After passing through the detector rolls the blanks pass to a moving chain which carries them on to the skiving, distributing, or other mechanism. At the start of the grading operation, the lower detector roll and transmission lever are both free to drop downward and admit the blank. A short time after the leading end of the blank has entered a ratchet mechanism locks the transmission lever against further downward movement. Thereafter during the passage of the blank through the rolls, the lower roll is free to move in both directions but only its upward movement is transmitted to the mechanisms which are to perform the further operations so that the operating mechanism, which may be a skiving knife, a stamping device, or an indicator, for example, is set in accordance with the minimum measured thickness of the blank.

Grading machines constructed substantially in accordance with the Nichols patent referred to above are in general use in the shoe industry, and give satisfactory measurement to the nearest half iron. Where greater accuracy is required, however, provision must be made for regulating the response of the indicating or operating mechanism to the motion of the detector rolls. The function of such a regulator is two-fold, to modify the grading response to meet particular operational requirements, and to compensate for various sources of error.

The efficiency of operations on certain types of leather may often be improved by setting the machine so as to depart somewhat from perfect grading. In skiving soles of widely varying thickness, for example, it may be advantageous to take a light cut from very thin soles and a deeper cut from thick soles. Another example of situation in which it may be expedient to modify the grading response is in grading flexible inner soles. In this case the blanks must be graded from a point as close as possible to the leading

2

end and the mechanism is, accordingly, set so that the locking pawl drops in early in the grading cycle. Under these conditions the grading mechanism, because of its inertia, may fail to reach a starting position adequate to account for the blank thickness, before the pawl engages, and undergrading results.

A major type of error is often encountered in grading curled leather which cannot be adequately flattened by the detector rolls under practicable spring pressures. Failure to flatten the sole results in "overgrading," that is the indicated thickness is greater than the actual minimum thickness of the blank. This effect can be compensated for by introducing a certain amount of "losing travel," that is, by setting the transmission mechanism so that the indicated thickness is less than the roll separation. Another error, which may be appreciable results from the compressibility of the leather. A certain amount of spring pressure is required to maintain positive contact between the detector rolls and the blank. The blank is, therefore, compressed as it passes through the detector rolls and it is apparent that a machine calibrated by steel gauge blocks will undergrade on leather, that is, the indicated thickness will be smaller than the actual thickness of the blank so that considerable unnecessary waste is incurred if the blanks are skived to the indicated thickness. This effect is known as the "linear travel error." Since the percentage error is constant for constant pressure, the magnitude of error increases in proportion to thickness of the blank. The effect of compressibility is aggravated by the increase in spring loading on the lower roll as it moves downward. This type of error cannot be allowed for in the initial calibration of the machine, because different types of leathers vary widely in firmness. Another effect ordinarily negligible, is known as the "cosine error." In the original machine the motion of the lower detector roll is communicated to the transmission lever by a pair of connecting rods which act on the lever at a fixed distance from the shaft which serves as the fulcrum. As the lever moves away from the horizontal, the horizontal distance between the shaft and the connecting rods is decreased, so that the mechanical advantage of the system is increased, giving rise to overgrading. Dimensional variations within normal manufacturing tolerances may also give rise to appreciable errors, unless some provision is made for adjusting the machine after it is assembled.

55 A regulating device for the Nichols type grader is described in Patent No. 2,180,591 to James W. Johnston. According to the Johnston patent a pair of slides are mounted in guideways on the underside of the transmission lever and provide a movable junction point between the connecting

rods and the transmission lever. The slides terminate in arms which ride on adjustable cams. As the lever moves away from the horizontal, the cams drive the slides so as to shift the point of application of the roll motion to the lever. As set forth in the Johnston patent, this device was described as a means to compensate for the cosine error, but it is primarily useful for altering the mechanical advantage of the transmission system for the purpose discussed above. The Johnston regulator has considerably improved the accuracy and flexibility of the Nichols type grader, but is subject to some objections. For example, the regulator increases the friction of the transmission mechanisms. The added friction interferes with the return to the start-grading position aggravating the aforementioned difficulty in grading flexible inner soles. Another disadvantage is that random variations are introduced into the grading response by backlash and lost motion between the moving parts of the regulator mechanism. Dirt and wear between the cams and the follower arms also cause difficulty. Furthermore, the range of adjustment is limited in the Johnston device so that two different models, having different slide lengths, are required to meet the demands of the shoe industry.

The object of this invention is to provide a regulating device which is adaptable to grading machines of the Nichols and similar types; which compensates more accurately and fully than regulators now in use, for the main sources of error in grading; which has a wide range of adjustments so that one type of regulator satisfies present commercial requirements; which adds no moving parts to the transmission mechanism; which is readily adjusted and maintains its setting accurately; which is simple in construction; and, which is impervious to wear and dirt.

Other advantages and novel features of the device will be apparent from the following description, with reference to the drawings, on which:

Fig. 1 is a partial cross-section through a grading machine, with the regulator installed, in the plane of one of the connecting rods, parts of the machine being broken away or schematically indicated for convenience;

Fig. 2 is a graph showing the effect of various errors and adjustments on the grading response;

Fig. 3 is a partial plan view of the transmission lever with the regulator attached; and

Fig. 4 is a front elevation of the parts shown in Fig. 3.

The operation of a machine of this type can be understood insofar as is necessary for an explanation of this invention by reference to Fig. 1. The blank to be graded is fed either manually or automatically from table 5 into detector rolls 6 and 7. Roll 7 is fixed to shaft 8, which is journaled in a fixed bearing in the frame 14, of the machine, and is continuously driven. Lower roll 6 is fixed to shaft 9 which is journaled at each end in boxes 12. The boxes slide in vertical guide ways 13. The lower roll is spring-pressed upward by means not shown. Rotary motion is imparted from the upper roll to the lower by wringer gears 10 and 11 fixed to shafts 9 and 8, respectively. A yoke 15 follows boxes 12. A pair of connecting rods 17 are journaled at their upper ends on pins 18 which are slidable along their longitudinal axes in yoke 15 and are secured by cotter pins 19. This arrangement permits horizontal motion between the yoke and

the connecting rods. The connecting rods project through openings 32 in the cross-piece 30 of transmission lever 23 and are threaded on their lower ends to receive ball nuts 21 and lock nuts 22. Seats 31 in slides 38 form, with ball nuts 21, separable universal joints between the connecting rods and the cross-piece 30 of transmission lever 23. A spring 41 tends to maintain separation between yoke 15 and lever 23 to the extent permitted by ball nuts 21. Lever 23 is journalled on a shaft 24 fixed in the frame of the machine, and carries gear sector 25 on its free end. Gear sector 25 engages with gear sector 26 which is fixed to a shaft 46, journalled in the frame of the machine. A ratchet 45 is also fixed to shaft 46. The motion of the shaft is transmitted through suitable linkages to any desired skiving, indicating, or other mechanism (not shown). During the grading operation, that is during the passage of a blank through rolls, pawl 28 engages ratchet 45 and locks lever 23 against downward motion. Upward motion of roll 6 will then be transmitted through yoke 15 and connecting rods 17, to lever 23, but subsequent downward motion of the rolls serves only to compress spring 41.

It is apparent from the foregoing description that the position of lever 23, and consequently the setting imparted to the indicating or other mechanism by the rotation of shaft 46, at the end of the grading operation, will correspond to the minimum thickness encountered by the rolls 6 and 7. Just before the blank leaves the rolls, shaft 46 is locked (by means not shown) until the desired further operations have been performed on the blank. The blank passes onto toothed chain 16 which carries it to the skiving, marking or other operating mechanism. When the machine is ready to admit the next blank, pawl 28 is momentarily released so lever 23 may drop down with roll 6 when the blank enters the rolls. Shortly after the blank enters, pawl 28 is dropped into engagement with ratchet 45, locking lever 23 against subsequent downward motion. A more detailed explanation of the operation of a grading machine of this type will be found in the Nichols patent previously referred to. Further description is omitted herein as not essential to an understanding of this invention.

Fig. 2 illustrates the effect of some of the errors previously mentioned herein. Assuming an incompressible blank and a linearly calibrated indicator, for example, a dial marked in equal angular increments to correspond to equal increments of motion of the lower roll, if the motion transmitted to the indicator were exactly proportionate to the motion of the roll, the plot of indicated thickness against blank thickness would be a line with a forty-five degree slope, here represented by the "perfect travel line." With the transmission mechanism shown, however, the radial distance from shaft 24 to rods 17 is fixed, so that, as lever 23 moves away from the horizontal, the horizontal distance between shaft 24 and the point of application of the vertical force transmitted through rods 17 becomes less and, therefore, the motion of gear sector 25 and consequently the indicator motion for a given roll travel becomes greater. The result of this departure from true proportionate transmission is illustrated by the curve designated "unregulated for cosine error." The curve is here shown exaggerated for the purpose of illustration. Over the limited range of rota-

tion through which lever 23 normally moves, the cosine error is relatively small and may be closely approximated by a straight line. If the material of the blank to be measured is compressible, as is the actual case, the separation of the roll will correspond not to the actual thickness of the blank, but to a certain substantially constant percentage of the thickness, the reduction in thickness for a given pressure being approximately proportionate to the thickness of the piece. The corresponding curve of indicated, against actual, thickness for a mechanism set by means of steel gauge blocks to give perfect travel, is illustrated by the curve designated "unregulated for linear travel error." In the actual case, the pressure on the blanks is not constant, but increases in proportion to roll travel according to the well-known formula for spring pressure. When operating on compressible blanks, therefore, the grading curve of a mechanism set for perfect travel on steel is approximately parabolic in form as shown by the curve designated "unregulated for linear travel error and increasing spring-loading." For the range of thickness which a machine of this type is expected to measure, however, this curve, like the "cosine error" curve can be closely approximated by a straight line. The effect of curls in the leather is, of course, largely unpredictable, but results in overgrading. The proper amount of losing travel to account for curls can best be determined by a few experimental measurements on the particular type of leather which is to be graded.

From a study of Fig. 2, it is apparent that the normal sources of error in grading can be compensated for, over the operating range by changing the slope of the grading curve, that is, by altering the mechanical advantage of the transmission system so that the indicator reading corresponds to a value somewhat more or less than actual roll travel. Figs. 1, 3 and 4, illustrate regulating mechanism suitable for accomplishing this result. The cross-piece 30 of lever 23 is built up on the underside, as seen in Fig. 4. The sides of the thickened section may be machined to form guides 41 for slides 38, or guides for the slides may be provided in any other well-known manner. In the example here shown, slides 38 are retained by plates 48, attached to lever 23 by screws 49. The slides carry seats 34 for ball nuts 21, and are joined together at the front by yoke 44. A threaded stud 33 is welded to yoke 44. This stud engages in adjusting screw 36 which is recessed and tapped. The screw 36 projects through back plate 34 and is retained by nuts 50 and 51. A curled hand knob 37 is provided on the outer end of screw 36. By turning screw 36, slides 38 may be moved in the longitudinal direction of lever 23, so altering the length of the lever arm between shaft 24 and rods 17. Since this arm is much shorter than the distance from shaft 24 to gear sector 25, a relatively small travel of slides 38 provides a considerable range of adjustment for the mechanical advantage of the transmission system. The corresponding curve of indicated, against actual, thickness may thus be made very close to the "perfect travel" curve for blanks of a reasonably uniform firmness, or any desired over-or-under-grading may be introduced. To facilitate setting a suitably calibrated indexing rod 52 may be attached to yoke 44. The rod 52 projects through a hole in plate

34. A nut 35 having a handle 53 is provided for locking screw 36 at the desired setting so that during the grading operation no motion takes place between the regulator slides and the transmission lever. The appreciable friction introduced by other regulators, for example the Johnston type, is thus entirely eliminated in this device.

Since certain changes may be made in the above-described article and different embodiments of the invention could be made without departing from the scope thereof, it is intended that all matter contained in the above description or shown in the accompanying drawing shall be interpreted as illustrative only and not in a limiting sense.

What is claimed is:

1. In a grading machine having a movable detector roll and a lever for transmitting the motion of the roll to other mechanisms; a yoke connected to said roll; a pair of pins axially slidable in said yoke; a pair of connecting rods, the upper ends of which are journalled on said pins; clearance holes in said yoke about said rods; ball nuts on the ends of said rods; slides mounted on the underside of said lever; seats for said nuts on the underside of said slides; means for shifting said slides longitudinally on said lever; and a mechanical lock for securing said slides in a desired position on said lever.

2. Apparatus according to claim 1 wherein said shifting means comprises: a yoke connecting said slides together; a threaded stud attached to said yoke; a back plate attached to said lever; and an adjusting knob journalled in said back plate and internally threaded to receive said stud.

3. Apparatus according to claim 2 wherein said knob is threaded on its shank and retained by a nut on the inner side of said plate, and the position of said slides is locked by means of a nut mounted on the shank of said knob on the outer side of said plate.

4. Apparatus according to claim 2 having an indicating rod attached to said yoke and projecting through a hole in said plate.

5. In a grading machine having a movable detector roll and a lever for transmitting the motion of the roll to other mechanisms; a pair of slides spaced apart and mounted on said lever adjustably in its longitudinal direction; a pair of correspondingly spaced connecting rods connected by universal joints to said slides; a connection between said roll and said rods slidable in said longitudinal direction; and a mechanical lock for securing said slides in a desired position on said lever.
